Primary Examiner — Anhdao Doan(74) *Attorney, Agent, or Firm* — Reinhart Boerner Van Deuren s.c.(57) **CLAIM**

I claim the ornamental design for an EKG viewing tool, as shown and described.

DESCRIPTION

FIG. 1 is a front perspective view of an EKG viewing tool;
 FIG. 2 is a rear perspective view thereof;
 FIG. 3 is a front view thereof;
 FIG. 4 is a rear view thereof;
 FIG. 5 is a left side view thereof;
 FIG. 6 is a right side view thereof;
 FIG. 7 is a top view thereof; and,
 FIG. 8 is a bottom view thereof.
